UNITED STATES PATENT OFFICE.

JOHN W. COAST, JR., OF TULSA, OKLAHOMA, ASSIGNOR, BY MESNE ASSIGNMENTS, TO DOHERTY RESEARCH COMPANY, OF NEW YORK, N. Y., A CORPORATION OF DELAWARE.

APPARATUS FOR DISTILLING OIL.

Application filed November 3, 1920. Serial No. 421,494.

This invention relates to apparatus for distilling oil and more particularly to scraping mechanism designed for use in stills.

In the operation of oil stills, especially those generally termed "pressure stills" in which distillation is carried on under pressure and at high temperatures to cause portions of the oil of high specific gravities and boiling points to be decomposed into oils of lower specific gravities and boiling points, substances such as tar, carbon, coke and the like are formed which tend to settle on the bottom of the still within the heating zone of the still. Inasmuch as such substances are poor conductors of heat, when they are allowed to accumulate on the shell of a still, they constitute a heat insulating medium which makes it at first difficult and then impossible to heat the contents of the still to a degree necessary to effect their proper distillation. Moreover, if carbonaceous material, such as carbon or coke, is allowed to remain undisturbed for any considerable length of time on the bottom of the still, it becomes baked on the still, and, in such an event, the portion of the still upon which the carbonaceous material is deposited is liable to be overheated and destroyed. In this respect, deposits of sediment are a source of great danger since they often lead to disastrous fires due to the ignition of oil escaping from a ruptured part of the still. It is, therefore, very important, particularly in the case of stills maintained in constant operation for long intervals of time as in the continuous distillation of oil, that all parts of the shell of a still be kept free from deposits of sediment.

It is an object of the present invention to provide in an oil still mechanism which may be operated during the process of distillation to remove from the inner surface of the shell of the still, and particularly from that portion of the still which constitutes the heating zone, all the carbon, coke and other solid matter which may gravitate upon it.

To this end, an important feature of the invention resides in providing a still with a scraping mechanism comprising members which will operate effectively to scrape the bottom of the still and which, to insure against loss of efficiency, are substantially self-cleaning. In the illustrated construction, moreover, separate means are provided for removing from the scraping members all

solid or semi-solid material which may adhere to them in spite of their self-cleaning action.

Another important feature of the invention is the provision of a scraping mechanism for a still or other receptacle which shall have chains disposed transversely of the receptacle and of the direction of movement of the scraping mechanism and acting to sweep before them any solid matter which may repose loosely on the bottom of the receptacle.

The invention further comprises other novel features of construction and arrangements of parts which will be hereinafter more fully described and claimed and are illustrated in the accompanying drawings, in which:

Fig. 1 is a plan view in section of a still showing the improved scraping mechanism arranged therein;

Fig. 2 is a view in longitudinal elevation of the interior of the still, certain of the parts being shown in section;

Fig. 3 is a transverse section of the still taken along the line 3—3 of Fig. 2 and looking in the direction of the arrows;

Fig. 4 is a transverse section of the still taken along the line 4—4 of Fig. 2 and looking in the direction of the arrows;

Fig. 5 is an enlarged view in front elevation of certain of the scraping members and the member which supports them; and,

Fig. 6 is a view in elevation showing the scraping members and the supporting members in transverse section;

In the accompanying drawings which illustrate a preferred embodiment of the invention, the body of the still is designated by the numeral 2 and is provided with oil inlet pipes 4 and 6 (Figs. 1 and 2). The still 2 is further provided with a vapor outlet 8 leading from the top of the still, and at the right hand end of the still (Fig. 2) are a manhole 9 and a tar or sludge outlet 10. The outlet 10 conducts the unvaporized oil from the still together with all the residual products resulting from the distillation. The still 2 is preferably substantially cylindrical in shape and is adapted to be supported in a horizontal position over the fire box. In the use of such stills, their end portions usually rest on the walls of the fire box which protect them from the heat of the fire and cause them to remain relatively cool as com-

pared with the portions of the bottom of the still intervening between the walls of the fire box and directly exposed to the heat of the fire.

- 5 In order to prevent substances such as tar, carbon, coke and the like from gravitating to the bottom of the still 2, and remaining undisturbed long enough to become baked on the shell of the still, a scraping mechanism is provided comprising scraper blades 12 received in openings in a supporting member 14 disposed transversely of the length of the still and of arcuate shape (Fig. 3) to conform with the bottom of the still.
- 10 The scraper blades 12 are formed with cutting edges 15 and when in operative position are inclined downwardly in the direction of their movement to cause them to operate after the manner of a hoe and effectively to remove from the shell of the still any material which may collect thereon. The scraper blades 12 are staggered (Figs. 1, 5 and 6), and, as shown in Fig. 3, they are nearer together at the central portion of the supporting member 14 where material is likely to collect in the greatest quantity and where it would be most quickly baked on the still, than at the end portions of the supporting member.
- 15 The supporting member 14 is of a length sufficient to extend upwardly along the sides of the still 2 as far as they are exposed to the flames of the fire, and the scraper blades 12 extend substantially to the ends of the supporting member so that they act on the shell of the still throughout the heating zone.

The scraping of the still 2 is effected by moving the supporting member 14 lengthwise of the still. To this end the supporting member is mounted on a carrier which, in the illustrated construction, comprises endless chains 16 arranged in parallelism in the still and trained over gears 18 and 20 on shafts 22 and 24 respectively. The shafts 22 and 24 are rotatably mounted in bearing brackets 25 projecting inwardly from the sides of the still. Motion is imparted to the shaft 22 and the chains 16 by means of a shaft 26 rotatable in a stuffing box 28 at the left hand end of the still, as shown in Fig. 1, and having a worm gear 30 meshing with a gear 32 on the shaft 22. A shaft 34 located between the shafts 22 and 24 carries gears 36 which assist in supporting the upper runs of the chains 16 and the parts carried by them.

The supporting member 14 may conveniently be attached to the chains 16 by yokes 38 (Figs. 3 and 6) and metal strips 40 each secured at one of its ends to one of the yokes 38 and at its other end to the supporting member.

In the form of the invention now preferred by me, a plurality of supporting members 14

are provided on the chains 16. Secured to the chains in advance of each of the supporting members in the direction of movement of the chains are transverse bars 42 which are connected by links 44 to the supporting members. The bars 42 and links 44 fixedly determine the positions of the supporting members 14 with reference to the chains 16 and prevent them from moving relatively to the chains in a horizontal direction under the strain imposed upon them while the scraper blades 12 are operating on the still.

The weight of each of the supporting members 14 and the parts associated with it tends to cause the chains 16 to sag as the supporting member passes over the central portion of the bottom of the still. In order to prevent this, a rail 46 is supported in horizontal position at each side of the still by brackets 48, and the supporting members 14 are equipped at their ends with grooved wheels 50 arranged to ride on the rails. With this construction, the rails 46 sustain the major portion of the weight of the supporting members during the scraping of the still. From the foregoing, it will also be understood that the rails 46 and wheels 50 maintain the supporting members during the operation of the blades 12 on the still at the same distance above the bottom of the still. In conjunction with the bars 42 and links 44, the above described parts maintain the supporting members 14, when in operative position, in constant relation to the bottom of the still, thereby enabling the scraper blades 12 to operate always with their maximum efficiency.

The scraper blades 12 are mounted loosely and independently in the openings of the supporting members 14 so as to permit their operative ends to be withdrawn by gravity into the supporting members when they are inverted by passing from the lower to the upper runs of the chains 16. The size of the blade receiving openings of the supporting members 14 is such that any material which may previously have adhered to the blades is removed therefrom by the supporting members as the blades are withdrawn into them. On account of the viscous character of the contents of the still, the scraper blades 12 tend to stick in the supporting members 14. In order to overcome this tendency, the supporting members are provided adjacent to each of the blades 12 with uprights 52 (Fig. 6) to which are pivoted levers 54 passing through openings in the blades and carrying weights 56. The weights 56 are heavy enough to insure that the blades 12 will be moved outwardly of the supporting members when they are in scraping position and reversely of such members when they attain the upper runs of the chains 16. It should be understood, however, that if any of the blades 12 should strike a rigid object

such, for example, as a protuberance on the shell of the still, the blade will be permitted to rise so as to pass over the obstruction without breakage. The reverse or cleaning movements of the blades 12 are arrested, when the operative ends of the blades have reached locations substantially flush with the adjacent surface of their supporting member, by a bar 58 normally overlying the levers 54 and secured at its ends to up-standing plates 60 forming parts of the supporting member. Each of the bars 58 is reinforced centrally by a metal strip 61 bolted to it and to the corresponding supporting member 14.

By making the blades 12 of relatively small width, as shown, they can be so weighted as to render them very reliable in their action. Inasmuch, however, as they are independently mounted in their carriers and are independently weighted, if, for any reason, one of the blades should fail to function properly, the effective operation of the other blades would not be interfered with.

In addition to the scraper blades 12, the supporting members 14 are provided adjacent to their ends with blades 62 of greater width than the blades 12. The blades 62 are located so far up the sides of the still where that material is not likely to be baked on the still within their range of action. Consequently, they do not need to be weighted and are secured to the supporting members 14 by pin and slot connections 63.

Means is preferably provided for removing from the edges of the blades 12 any material which may still cling to them after the withdrawal of the blades into the supporting members and for removing from the supporting members any material which may be deposited upon them by the blades. This means may have various forms but, in the illustrated construction, it comprises a pump 64 operated by a shaft 65 and acting to withdraw oil from the still 2 through a pipe 66 and to deliver it through a pipe 67 to nozzles 68. The nozzles 68 are arranged to direct the oil in streams against the supporting members as they pass from the lower to the upper runs of the chains 16.

Material which is detached from the bottom of the still by the scraper blades 12 may pass between the blades and remain on the still bottom. This and any other material which may lie loosely on the shell of the still should be removed. Accordingly, a frame 70 is secured to the endless chains 16 in transverse relation to the still 2 and is equipped with chains 72 disposed transversely of the still and arranged to drag on the bottom of the still so as to sweep all such material to the residuum outlet pipe 10. As shown, the frame 70 (Fig. 4) is constructed with an arcuate portion 73 conforming with the bottom of the still and having

a bracket 74 extending forwardly from it in the direction of movement of the chains 16. In the illustrated construction, a pair of chains 72 are shown each attached at one end to the forward end of the bracket 74 of the frame 70 and at its other end to a pin 75 depending from the end of the arcuate portion 73. It is apparent, however, that a single chain may be used extending from one of the pins 75 to the other and attached at its central portion to the bracket 74 of the frame.

The chains 72 are made longer than the distance from the bracket 74 of the frame 70 to one of the pins 75 so that they may drag along the bottom of the still 2 behind the bracket 74. In order to maintain the frame 70 in fixed position relatively to the chain 16 during the operation of the chains 72 on the still, a bar 76 is secured to the chains 16 in advance of the frame and is connected with the arcuate member 73 of the frame by links 78. The endless chains 16 are relieved of the weight of the frame 70 as it passes along the bottom of the still 2 by metal strips 80 extending upwardly from the ends of the arcuate member 73 and provided at their upper ends with wheels 82, riding on the rails 46.

Inasmuch as the end portions of the bottom of the still, for the reasons above indicated, are comparatively cool, material is not likely to be baked thereon. On the contrary, any material which may gravitate upon such portions of the bottom of the still may ordinarily be moved readily along the still. It will be noted that the front end of the bracket 74 is only slightly to the rear of the pivotal connection between the upper end of the link 78 and the endless carrier 105 while the scraper blades 15 are much farther to the rear of the corresponding pivotal connection at the upper end of the link 44. As a consequence certain end portions of the still which are not reached by the scrapers 110 15 will be reached by the chains 72, more particularly by that section of the chain which is secured below the front end of the bracket 74.

Although the scraping mechanism has been described as operating during the process of distillation and is preferably so operated, it is evident that it may be employed to scrape the still at any time, including occasions when distillation is not being carried on.

Having fully described my invention what I claim and desire to secure by Letters Patent of the United States is:

1. An apparatus for distilling oil comprising a still, a supporting member shaped to conform substantially with the heating surface of the still, an endless carrier for the supporting member, means for operating said carrier to move the supporting member

adjacent to the heating surface of the still, scraper blades mounted loosely in the supporting member for movement relatively to the supporting member so as to follow the contour of the still and inclined downwardly in the direction of movement of the supporting member, and means for weighting the blades to maintain them normally in engagement with the heating surface of the still when said member is moving adjacent thereto.

2. An apparatus for distilling oil comprising a still, a supporting member shaped to conform substantially with the heating surface of the still, an endless carrier for the supporting member, means for operating said carrier to move the supporting member adjacent to the heating surface of the still, blades mounted loosely on the supporting member for scraping the bottom of the still, and means for weighting the blades to cause them to follow the contour of the heating surface of the still when said member is moving adjacent thereto, said weighting means being constructed to allow the blades to move independently of each other toward and from the still.

3. An apparatus for distilling oil comprising a still, a supporting member, blades carried by the supporting member for scraping the bottom of the still, an endless carrier for moving the supporting member along the still, and means separate from the carrier for sustaining the weight of the supporting member during its movement along the still.

4. An apparatus for distilling oil comprising a horizontally arranged still, supporting member, blades carried by the supporting member for scraping the bottom of the still, endless carriers running longitudinally of the still for moving the supporting member along the bottom of the still and means above the lower runs of the carriers for sustaining the weight of the supporting member during its movement along the still.

5. An apparatus for distilling oil comprising a still, a supporting member formed with blade-receiving openings, means for moving the supporting member adjacent to the bottom of the still from one end of the still to the other and for returning the supporting member in inverted position to the first-mentioned end of the still, and scraper blades mounted loosely in the openings of the supporting member so as to gravitate against the bottom of the still when the supporting member is in operative position and to be withdrawn by gravity into the supporting member when the supporting member is inverted, said blades and the openings of the supporting member being of such relative sizes that upon withdrawal of the blades into the supporting member, material which may previously have adhered to the blades

will be removed therefrom by the supporting member so as to render the blades substantially self-cleaning.

6. An apparatus for distilling oil comprising a still, a supporting member movable along the bottom of the still, blades loosely mounted on the supporting member for scraping the bottom of the still, means for moving the supporting member from one end of the still to the other and to return the member in inverted position from the last-mentioned to the first-mentioned end, weighting means constructed to maintain the blades normally in contact with the bottom of the still while the supporting member is in scraping position and to effect reverse movement of the blades with respect to the supporting member when the supporting member is in inverted position, and means for limiting the reverse movement of the blades.

7. An apparatus for distilling oil comprising a still, a supporting member, means for moving the supporting member adjacent to the bottom of the still from one end of the still to the other and for returning the supporting member in inverted position to the first-mentioned end of the still, blades carried loosely by the supporting member so as to cause their ends to project from the supporting member during its movement along the bottom of the still to scrape the still and to withdraw into the supporting member upon inversion of the supporting member, and means for removing from the supporting member any material which may be deposited upon it by the blades.

8. In a mechanism for scraping a receptacle, a supporting member, means for moving the supporting member adjacent to the bottom of the receptacle from one end of the receptacle to the other and for returning the supporting member in inverted position to the first-mentioned end of the receptacle, blades carried loosely by the supporting member so as to cause their operative ends to project from the supporting member during its movement along the bottom of the receptacle to scrape the receptacle and to withdraw into the supporting member upon inversion of the supporting member, said blades and said supporting member being so constructed and arranged that upon the withdrawal of the ends of the blades into the supporting member material which may have previously adhered to the blades is removed therefrom, and means for limiting the further withdrawal of the blades into the supporting member after the operative ends of the blades have been moved substantially into line with the adjacent surface of the member.

9. An apparatus for distilling oil which comprises a still, a supporting member, means for moving the supporting member

along the bottom of the still from one end of the still to the other and for returning the supporting member in inverted position to the first-mentioned end of the still, blades 5 carried by the supporting member for scraping the still, said blades and said supporting member being constructed and arranged to cause the operative ends of the blades to be withdrawn into the supporting member 10 upon inversion of the member and to cause material previously adhering to the blades to be removed by the supporting member, means for limiting the further movement of the blades after their operative ends have 15 been moved substantially into line with the adjacent surface of the supporting member, and means including a plurality of nozzles for withdrawing oil from the body of oil in the still and directing it against the surface 20 of the supporting member to prevent material from accumulating on the supporting member.

10. An apparatus for distilling oil comprising a still, an endless carrier mounted 25 for movement lengthwise of the still, a substantially hollow supporting member carried by the endless carrier, and a plurality of -scraping members passing through the top and bottom walls of said supporting member.

11. An apparatus for distilling oil comprising a still, an endless carrier mounted for movement lengthwise of the still, a support on the carrier, members carried by the 35 support for scraping the still, and drag chains mounted on the endless carrier for sweeping loose material along the still.

12. In a mechanism for scraping a receptacle, an endless carrier mounted for move-

ment lengthwise of the receptacle, scraping 40 members carried by the endless carrier and disposed to engage the inner surface of the lower portion of the receptacle, transversely disposed chains on the carrier arranged to drag upon the inner surface of the lower 45 portion of the receptacle, and means for operating the carrier.

13. An apparatus for distilling oil comprising a still, an endless carrier mounted for movement lengthwise of the still, scraping 50 members carried by the endless carrier and disposed to engage the inner surface of the lower portion of the still from a point spaced from one end of the still to a point spaced from the other end of the still, and trans- 55 versely disposed chains on the carrier arranged to drag upon the inner surface of the bottom of the still including the portions of the bottom of the still adjacent to its ends which are not operated upon by the 60 scrapers.

14. An apparatus for distilling oil comprising a still, an endless carrier mounted for movement lengthwise of the still, means for operating the carrier, a frame mounted 65 transversely on and projecting outwardly from the carrier and having a central portion extending forwardly from the frame and disposed to move close to the bottom of the still adjacent to the vertical plane 70 of the centre line of the still, and chains secured to the central portion of the frame and to other portions of the frame disposed laterally of the central portion, said chains being arranged to drag upon the bottom of 75 the still.

In testimony whereof I affix my signature.
JOHN W. COAST, JR.
